CHAIN CANDLES

Siegfried Steinhart, Obere Ganshalde 14,
Krumbach, Germany 8908

Filed Aug. 22, 1972, Ser. No. 282,659

Claims priority, application Germany Feb. 25, 1972;
Mar. 10, 1972

Term of patent 14 years

Int. Cl. D26—04

U.S. Cl. D73—1 B

The figure is a side elevational view of a chain candle showing my new design, the appearance being the same from all sides.

I claim:

The ornamental design for chain candles, as shown and described.
